UNITED STATES PATENT OFFICE.

OSCAR A. ROHRER, OF WAVERLY, ILLINOIS, ASSIGNOR OF ONE-HALF TO JOHN H. SHUTT, OF WAVERLY, ILLINOIS.

SUCTION CLEANING-MACHINE.

1,053,649.

Specification of Letters Patent. Patented Feb. 18, 1913.

Application filed April 22, 1912. Serial No. 692,427.

To all whom it may concern:

Be it known that I, OSCAR A. ROHRER, a citizen of the United States, residing at Waverly, in the county of Morgan and State 5 of Illinois, have invented a new and useful Suction Cleaning-Machine, of which the following is a specification.

This invention relates to improvements in suction cleaning machines, the primary object of the same being the provision of a portable machine adapted to be propelled over the surface cleaned and provided with a suction nozzle having a yielding tension upon the surface, such tension being increased or diminished, due to the elevating or lowering of the hand gripping portion of the handle.

With the foregoing and other objects in view which will appear as the description 20 proceeds, the invention resides in the combination and arrangement of parts and in the details of construction hereinafter described and claimed, it being understood that changes in the precise embodiment of the invention herein disclosed can be made within 25 the scope of what is claimed without departing from the spirit of the invention.

In the drawings—Figure 1 is a top plan view of the complete machine with only a portion of the operating handle shown. Fig. 30 2 is a side elevation of the complete machine with one of the drive wheels removed. Fig. 3 is a section taken on line 3—3 of Fig. 2, through the dust receptacle and suction creating device. Fig. 4 is an enlarged detail view of the eccentric and means for actuating the pistons of the suction creating device. Fig. 5 is an enlarged detail view of the supporting frame with the nozzle attached thereto. Fig. 6 is an enlarged detail sectional view through the eccentric and straps illustrating the anti-frictional bearings interposed therebetween.

Referring to the drawings, the numeral 1 45 designates the two longitudinal strips of the frame of the suction cleaning machine, which is properly spaced at their forward ends by means of the yoke plates 2 and 18, while the rear end is held by means of the two angle 50 plates 3, which provide a means for the connection of the operating handle 4 thereto.

Journaled in the strips 1 near the forward end thereof, are the two stub shafts 5 which carry the drive wheels 6, which are the only 55 supporting wheels for the suction cleaning

device, and carried by each one of the respective drive wheels is a large internal gear 7, by means of which the suction creating device, as will presently appear, is operated by the rotation of the drive wheels as the 60 machine is pushed back and forth over the surface being cleaned.

Two brackets 8, are connected to the under side of the plates 1 to the rear of the stub shafts and have journaled therein a single 65 transversely disposed shaft 9, upon whose outer ends are keyed the small pinions 10, which are in mesh at all times with the teeth of the internal gears 7 of the drive wheels 6. By this means it will be seen that 70 the rotation of the respective drive wheels will operate the shaft 9.

Keyed upon the shaft 9 intermediate of its ends, is an eccentric 11 which has disposed thereabout the two part strap 12, the 75 anti-frictional bearings 13, being interposed between the periphery of the eccentric 11 and the strap 12 to reduce the friction at such point during the rotation of the eccentric and the consequent oscillation of the 80 strap. The strap 12 is provided with the two lugs 14 between which is pivoted the rear end of the connecting rod 15, whose forward end is connected to the crank 16 of the shaft 17. The shaft 17, as clearly shown 85 in Fig. 4, is journaled between the plates 2 and 18. Keyed upon the shaft 17, near the upper end thereof, and within the plate 2 is the cross-head 19. It will thus be seen that the rotation of the shaft 9 imparting motion to the eccentric 11, will produce in the shaft 17 an oscillating movement so that the cross-head 19 will be oscillated similarly to a walking beam.

A metal casing 21 for properly supporting the suction creating devices 38 and the dust and dirt receptacle 23 is provided, the same being composed of an elongated sheet metal member adapted to be slid over the lower end of the respective suction creating devices and is properly supported between the two longitudinal strips 1 of the frame. The slot 22 is provided in the casing 21, the purpose of which will presently appear.

As clearly shown in Fig. 3, the dust and 105 dirt collecting cylinder 23, is provided with the removable cap or closure 24 at the rear end thereof, the nozzle attaching tube 25 being connected to the chamber 23 near the rear end thereof and at its upper side so as 110

to fit within the recess or slot 22 of the upper portion 21 of the casing. Leading from the tube 25 is a flexible conduit or hose pipe 26, whose normal tendency is to hold the floor engaging tool or nozzle 27 carried in the outer free end thereof, downwardly upon the surface traversed. The nozzle 27 is connected to the outer ends of the arms 28, whose inner ends are pivotally connected as at 29 to the inner ends of the stub shafts 5, so that by reason of the tension or resiliency of the flexible conduit 26 (dotted lines Fig. 2), the nozzle 27 will be held downwardly regardless of the positioning of the frame and handle 4, so that persons of various heights may efficiently operate the machine during the back and forth movement thereof over the surface being cleaned. It is also evident, that a slight upward movement of the handle 4 will impart a greater pressure so that the nozzle 27 may be held more closely upon the surface being cleaned.

The cylinder 23 has mounted therein a ring 30, which slidably fits tightly against the inner walls of the chamber 23 and connected thereto is a spring handle 31, whereby the said ring 30 with the air filtering and dust receiving bag 32 may be placed within, or withdrawn through, the open end of the chamber 23 sealed by the cap or closure 24. The bag 32 may be composed of any desired screening fabric and may be held by any form of frame as desired, it being open at the end adjacent the cover 24 so that the dust and dirt entering through the nozzle and nozzle tube 26 will be conducted as indicated by the arrows in Fig. 3, into the bag 32 whence the filtered air passes through the port 33 of the chamber 23. Thus the bag 32 will act both as an air filtering means and a dust and dirt receptacle.

Disposed in opposite positions longitudinally of the intermediate portion of the cylinder 23, are the two air conducting channels 34 in whose walls 35 at the rear ends thereof, are provided the valve controlled ports 36, the valves in said ports being disposed to open outwardly to permit the passage of the air through said ports and the by-passes 37 and into the respective rear ends of the cylinders of the suction creating devices 38. The two suction creating devices are disposed oppositely upon each side of the dust and dirt receptacle and are each provided with the valve outlet ports 39, so that air can escape upon the exhaust stroke of the plunger 20. A plunger 40 is mounted for reciprocation in each one of the cylinders and these plungers are operably connected to the respective terminals of the double lever 19 through the connecting rods 41, these being so disposed that one is in the act of drawing the air through the suction nozzle while the other is expelling the air

within the chamber of its respective cylinder through the exhaust port 39. By this means it will be seen that a continuous flow of air is drawn through the nozzle 27 and into the chamber 23 to be finally expelled through the respective valve controlled exhaust ports 39 of the suction creating devices 38.

What is claimed is:

1. A portable suction cleaning machine, having a frame, a handle for propelling the machine, a pair of wheels supporting the frame, a suction creating device carried by the frame and operably connected to the wheels, a suction nozzle, a pair of arms pivoted to the axles of the wheels and having their free ends connected together by the nozzle and bodily carrying the nozzle, and a resilient conduit connecting the nozzle to the suction creating device and having a yielding tension to hold the nozzle toward the surface traversed. 75 80 85

2. A portable suction cleaning machine, having a frame mounted upon wheels, a handle connected to the rear end of the frame, a suction creating device mounted upon the frame, a pair of arms having their inner ends pivotally connected to the frame, a transversely disposed nozzle connecting the free ends thereof for movement in unison, and a resilient conduit having one end connected to the nozzle and the other end to the suction creating device, said conduit exerting a tension to hold the free ends of the arms downwardly and the nozzle toward the surface traversed. 90 95 100

3. A portable suction cleaning machine, having a frame mounted on wheels, a handle connected to the rear end of the frame, a suction creating device carried by the frame and operated from the wheels, a pair of arms having their inner ends pivotally connected to the frame intermediate of the ends of the frame, a transversely disposed nozzle connecting the free ends of the arms together, and a resilient conduit having one end connected to the nozzle and the other end to the suction creating device, said conduit exerting a tension to hold the nozzle toward the surface traversed, the pressure of the nozzle upon the floor being increased by the elevation of the handle and the consequent bending of the conduit. 105 110 115

4. A suction cleaning machine, having a pair of drive wheels, an open frame pivoted intermediate its ends to the axles of the wheels, a handle rigidly connected to one end of the frame, a suction creating device carried by the frame and operably connected to the wheels, two arms having their upper ends pivoted to the axles with their free ends extending toward and beyond the other end of the frame, a nozzle connecting the free ends of the arms together, and an elastic conduit having one end connected to the suc- 120 125 130

tion creating device and the other end connected to the nozzle, said conduit forming a resilient connection between the nozzle and the frame, whereby the elevation of the handle regulates the pressure of the nozzle upon the surface traversed.

In testimony that I claim the foregoing as

my own, I have hereto affixed my signature in the presence of two witnesses.
